COMBINED REFLECTOR AND LENS

Sidney A. Heenan, Park Ridge, Ill., assignor to Amerace Esna Corporation, New York, N.Y.

Filed Sept. 2, 1971, Ser. No. 177,521

Term of patent 14 years

Int. Cl. D29—02; D26—05

U.S. Cl. D72—1 E

FIG. 1

FIG. 2

FIG. 3

FIG. 4

FIG. 5

FIG. 6

FIG. 1 is a front elevational view of a combined reflector and lens incorporating my new design;

FIG. 2 is a cross-sectional view taken on line 2—2 of FIG. 1;

FIG. 3 is a cross-sectional view taken on line 3—3 of FIG. 1;

FIG. 4 is a front elevational view of a second embodiment of my design;

FIG. 5 is a cross-sectional view taken on line 5—5 of FIG. 4; and

FIG. 6 is a cross-sectional view taken on line 6—6 of FIG. 4.

I claim:

The ornamental design for a combined reflector and lens, substantially as shown and described.
